UNITED STATES PATENT OFFICE.

JAMES EDWIN GIBBS, OF HUNTINGTON, WEST VIRGINIA.

SASH-LOCKING DEVICE.

No. 922,882.

Specification of Letters Patent.

Patented May 25, 1909.

Application filed September 23, 1908. Serial No. 454,395.

To all whom it may concern:

Be it known that I, JAMES EDWIN GIBBS, a citizen of the United States, residing at Huntington, in the county of Cabell and 5 State of West Virginia, have invented a new and useful Sash-Locking Device, of which the following is a specification.

The present invention relates to means for locking the sashes of a window against 10 movement and in different adjusted positions.

The primary object of the present invention is to provide a simple and effective structure of the character set forth, that can 15 be readily applied to a window frame without any great alteration of the same, is invisible from the exterior of the window and cannot be operated from the outside.

The preferred form of construction is illustrated in the accompanying drawings, 20 wherein:—

Figure 1 is a view in elevation of the inner face of a portion of a window frame, with 25 the sashes removed and showing the lock in elevation. Fig. 2 is a sectional view on the line 2—2 of Fig. 1. Fig. 3 is a vertical sectional view on the line 3—3 of Fig. 1. Fig. 4 is a rear elevation of the locking device complete. Fig. 5 is a detail sectional view 30 on the line 5—5 of Fig. 4. Fig. 6 is a detail perspective view of the sash holding element.

Similar reference numerals designate corresponding parts in all the figures of the 35 drawings.

In the embodiment illustrated, the window frame 7 may be of any well known form, and contains the usual upper and lower sashes 8 separated by a parting strip 9 that 40 is seated in a groove 10. A socket 11 is formed in the frame and intersects the groove, being wider than said groove, as clearly illustrated in Fig. 1. Below this socket, the opposite side walls of the groove 45 are provided with recessed seats 12. A dovetailed groove 13 is formed in the frame transversely of the groove 10, and extends through the inner side of the frame below the inner sash retaining strip 14. It will be 50 observed particularly by reference to Figs. 2 and 3 that the edges of the sashes adjacent to the wall of the frame constructed as above described, have sockets or seats 15.

A sash holding device is provided that 55 preferably consists of a strip of thin highly tempered steel doubled at its central por-

tion and formed into a comparatively large ring 16 that fits snugly into the socket 11, and consequently extends entirely across the groove 10. The ring is maintained in 60 the socket by means of nails 17, or other suitable fasteners extending over said ring. Depending divergently disposed arms 18 extend from the ring and are located in the groove 10. The lower free ends of said 65 arms are oppositely outturned and bifurcated to produce sets of lips or teeth 19 and 20, the latter being preferably longer than the former, as shown in Fig. 6. The lips or teeth 19 are engaged in the seats 12, while the 70 lips or teeth 20, which are carried by projecting portions 21 on the arms 18, are arranged to engage in the different seats 15 of the sashes. The parting strip 9 is cut away 75 at the place occupied by the sash locking device in order that it will not in any manner interfere with the operation thereof, as hereinafter described.

A channeled actuating slide 22 is employed having its flanges 23 flared and operating in 80 the dovetailed groove 13. This device or slide 22 has the upper portion at its inner end cut away, as shown at 24, producing a pair of shoulders 25 that bear against the lower ends of the arms 18. It will thus be 85 evident that upon the outward movement of said slide, the inner arm will be moved inwardly so as to carry its tooth 20 out of engagement with the lower sash, while on the inward movement of the slide, the tooth 20 90 of the outer arm will be carried out of engagement with the upper sash. Under normal conditions, however, the arms 18 are spread apart, so that both the teeth are in engagement with their respective sashes. 95

Fulcrumed between its ends on the slide 22 and located in the channel thereof is a holding lever 25^a, the outer end of which is provided with a looped portion 26 forming a finger piece, the inner end being upturned as 100 shown at 27 and adapted to engage between the lower ends of the arms 18 to prevent their opposite movements toward each other. A spring 28 of any suitable construction is 105 preferably employed to bear against the lever 25^a so as to urge the end 27 between the arms.

In applying this device to a window frame, it is only necessary to cut out the socket 11, the seats 12, the groove 13 and cut away the 110 parting strip, whereupon the elements of the locking device can be readily introduced into

place and secured, the only securing means necessary being the nails or pins 17. When the teeth 20 are in engagement with both sashes, said sashes are securely held against 5 movement. To unlock either, it is only necessary to raise the finger piece 26 and move the slide either in or out, whereupon one of the teeth 20 will be disengaged from the sash and its movement will be permitted. 10 When relocked, however, the spring 28 will act to automatically throw the lever 25^a to a position with the end 27 between the arms. This feature is of considerable importance, as it prevents the retaining strip for the outer 15 sash being pried up, and an instrument introduced beneath it to force the tooth 20 rearwardly, and thus permit the lowering of the sash. The particular construction and arrangement of the locking element is also 20 important. By having a large ring 16, there is no danger of the device rocking on an axis disposed longitudinally of the groove 10, and this ring engaging in the opposite walls of the groove, constitutes holding means that prevents the longitudinal movement of the element. The teeth 19 also prevent such longitudinal movement, and furthermore act as 25 positioning devices inasmuch as both cannot be disengaged from their seats at the same time. By having the ring 11 uppermost and the locking element disposed adjacent to the joint between the upper and lower sashes when closed, such element is 30 always covered and cannot be seen from the outside of the window. The actuating device also has its advantages. In the first 35 place, it is effectively retained in position because of its dovetailed formation, and the lever being located in the channel, is entirely 40 out of the way, and a smooth outer surface is provided that will not interfere with the free movement of the sash thereover.

From the foregoing, it is thought that the 45 construction, operation and many advantages of the herein described invention will be apparent to those skilled in the art without further description, and it will be understood that various changes in the size, shape, proportion and minor details of construction 50 may be resorted to without departing from the spirit or sacrificing any of the advantages of the invention.

Having thus fully described my invention, what I claim as new, and desire to secure by 55 Letters Patent, is:—

1. The combination with a window frame having a groove for a parting strip, of sashes mounted in the frame, and a sash locking device comprising a yielding metallic strip 60 doubled to form an enlarged ring that is located in and extends completely across the groove, said device having outturned sash engaging terminals, and means for moving the terminals.

65 2. The combination with a window frame

having a groove for a parting strip and a socket that intersects and is wider than the groove, of sashes mounted on the frame, and a sash locking device comprising a yielding metallic strip doubled into an enlarged ring 70 that is located in the socket, fastening devices arranged over the opposite sides of the ring, said locking device having outturned sash engaging terminals, and means for moving the terminals.

3. The combination with a window frame having a groove and a seat formed in one wall of the groove, of a sash that operates in the frame, and a sash locking device operating in the groove, said device having a portion 80 that engages the sash to hold it and having a portion movable into and out of engagement with the seat.

4. The combination with a window frame having a groove and seats formed in the opposite walls of said groove, of sashes operating 85 in the frame, and a sash locking device comprising a pair of arms located in the groove and having outturned terminals, portions of which engage the sashes to hold the 90 same, and other portions engaging in the seats.

5. The combination with a window frame having a groove for a parting strip, a socket 95 that intersects and is wider than the groove and seats formed in the opposite walls of the groove below the socket, of sashes operating in the frame on opposite sides of the groove, and a sash locking device comprising a yielding metallic strip doubled between its ends 100 to form an enlarged ring that is engaged in the socket and depending arms that are located in the groove, said arms having outturned terminals, portions of which engage the sashes and other portions engaging in the 105 seats, and means for moving the arms toward each other.

6. The combination with a window frame, and a sash sliding therein, said frame having a transverse dovetailed groove, of a sash 110 locking device mounted in the frame, and an actuator for the said locking device provided with flared flanges that operate in the groove and retain the locking device in place.

7. The combination with a pair of oppositely moving independently operable sash locking elements, of means for operating either one or the other of the same, and a device movable to a position between the elements to hold them in their operative positions.

8. The combination with a pair of oppositely moving independently operable sash locking elements movable toward and from each other, of means for moving the same, 125 and a device carried by the moving means and movable to a position between the elements to hold them separated and to retain the said means against movement.

9. The combination with a sash engaging 130

and locking element movable into and out of engagement with a sash, of a separate actuating device for moving the element, and a holding device movably mounted on the actuating device and movable to a position to lock the element in engagement with the sash and to hold the actuating device against movement.

10. The combination with a sash engaging and locking element movable into and out of engagement with a sash, of an actuating device for moving the element, and a holding device pivotally mounted on the actuating device and movable into engagement with 15 the element to hold the same against movement.

11. The combination with oppositely movable sash locking elements, of a device for moving the same toward and from each other, and a holding device pivotally mounted on the actuating device and movable to a position between the same for locking them against movement toward each other.

12. The combination with a window frame having a groove for a parting strip, a socket that intersects and is wider than the groove, and seats formed in the opposite walls of the groove, of a sash locking device comprising

a strip of yielding sheet metal having its central portion doubled into a ring that is located in the socket, and arms extending longitudinally in the groove, said arms having outturned terminals, portions of which operate in the seats, and other portions engaging the sashes, securing means engaging over the ring to hold the locking device in place, a channeled actuating device operating transversely of the arms and engaging the same to move them in opposite directions toward each other, a holding lever pivotally mounted in the channel of the actuating device and having an upturned terminal that moves between the arms to prevent their movement toward each other, said lever having an outer exposed handle, and a spring carried by the channeled actuating device and bearing against the lever to urge the terminal between the arms.

In testimony, that I claim the foregoing as my own, I have hereto affixed my signature in the presence of two witnesses.

JAMES EDWIN GIBBS.
